UNITED STATES PATENT OFFICE.

EPHRAIM WILLIAM HAVERS, OF LONDON, ENGLAND.

GAS-VALVE.

1,079,337.

Specification of Letters Patent. Patented Nov. 25, 1913.

Application filed September 7, 1912. Serial No. 719,047.

To all whom it may concern:

Be it known that I, EPHRAIM WILLIAM HAVERS, a subject of the King of Great Britain, residing at London, England, have 5 invented new and useful Improvements in Gas-Valves, of which the following is a specification.

This invention relates to valves such as are used for controlling the passage of gas 10 to a gas burner or gas fire, for example. Such valves may be operated from any distance by suitable means such as the electrical energy produced by the closing of an electric circuit, for example. It may be used in combination with any suitable igniter, electric or otherwise, and forms when so used a complete apparatus. It is often especially desirable in such apparatus to provide a temporary supply of gas for the igniter, or for a 20 flash by-pass, for example, irrespective of the main supply to the burner, and my invention consists of devices by which this temporary supply is obtained in a simpler and more effectual manner than heretofore.

25 According to my invention I arrange the valve as follows:—Instead of allowing the operating impulse—such as the force exerted by an electro-magnet—to complete the movement of the valve at one operation, it is caused to perform only one-half (or thereabout) of its work directly and to store up by any suitable means, such as gravity or a spring for example, the force needed to complete the movement of the valve, this latter force being liberated only on the cessation of the impulse or the breaking of the electric circuit. In the turning-on impulse it will be seen that by operating the valve in two steps from one impulse, an intermediate 35 position is formed, and in this intermediate position the valve is allowed to pass the secondary supply of gas required. When the valve is in this intermediate position the main supply may be cut off but it is preferably turned partly on. The turning-off impulse is similar to the turning-on impulse, and the operations will necessarily follow one another.

The valve is applicable to any form of 50 igniter, and the types of valves hereinafter referred to are only by way of example.

In order that my invention may be clearly understood, I will now proceed to describe the same with the aid of the accompanying 55 sheet of drawings, in which—

Figure 1 shows one form of valve with op-

erating mechanism applied thereto, the valve being in its "off" position; Fig. 2 is an enlarged view of the valve illustrated in Fig. 1 turned into the "intermediate" position, that is to say establishing communication between the main gas supply and the by-pass or secondary supply; Fig. 3 a similar view to Fig. 2 but with the valve turned into the "open" position, that is to say establishing communication between the main gas supply and the main burner; Fig. 4 a sectional side elevation of Fig. 1 the valve being shown in section; Fig. 5 a section on line A—B of Figs. 1 and 4 with the valve omitted; Fig. 6 shows a modified form of valve; Fig. 7 a transverse section of Fig. 6; and Fig. 8 a plan view of a flat disk type of valve, such as is frequently used in gas igniting apparatus of the kind described.

Referring to Figs. 1 to 5, *a* is a square hollow tube provided at or near the middle of its length with a partition *b* which separates the source of supply *c* from the outlet *d* supplying the burner. The tube *a* is provided with holes *e* hereinafter referred to, which are controlled by the valve *f* which is pivotally mounted in the center of the partition *b* at the point *g*. The valve *f* is closed in at its back by a cover *h* which may be fixed in any convenient manner to the valve or be integral therewith. The face of the valve is provided with any suitable number of holes *i* (four being shown in the drawing) adapted to be brought alternately into and out of register with the similar number of holes *e* formed in the tube *a* above and below the partition *b*. One or more holes *j* is or are also provided in the partition *b* of the tube *a* by which communication may be made with the valve for establishing the secondary supply for the igniter, flash by-pass, or the like. It will be seen that when gas is introduced at *c*, and the holes *i* and *e* are out of register as in Fig. 1, the gas will be cut off from the burner and by-pass. When the valve is in the position indicated in Fig. 2 gas is free to pass from the supply *c* through the holes *i* *e* and *j* to the igniter *k*, or the like, and also a partial supply *d* to the main burner. When the valve is in the position illustrated in Fig. 3, gas is free to pass from the supply *c* through the holes *i* and *e* into the hollow of the valve *f* from the top side of the partition *b* to the lower side which establishes the main supply *d* to the gas burner, for example. The valve contact surface and

the surface on the tubular body *a* are of course ground together, and may be held in close contact by means of the spring *m* mounted on the axis of the valve or otherwise as may be convenient.

In the apparatus illustrated in the drawings, it is assumed that the operating impulse is the force exerted by electro-magnets. This force operates the valve by two distinct steps, and suitable mechanism for accomplishing this is shown clearly in Fig. 1, wherein the action is as follows:—In the turning-on impulse the armature *n* lifts when the coils *o* are energized, and in lifting or being attracted toward the coils operates the valve *f* by means of the pawl *p*, turning the same into the intermediate position, as shown in Fig. 2. Half the traverse of the valve is thereby effected, and by the action of lifting or attracting the armature toward the coils *o*, the necessary energy to effect the completion of the traverse or stroke of the valve is stored up by reason of the weight of the said armature, or by other suitable means of storing energy. It will be observed that on the opposite side of the ratchet wheel of the valve is provided another pawl *q*, which by reason of the lifting of the armature *n* has been brought by this time into engagement with the next tooth of the ratchet wheel. When the impulse ceases this stored up force completes the traverse of the valve by the action of the pawl *q* and the falling or receding armature *n*, when the position of the valve becomes as illustrated in Fig. 3. During the intermediate position obtained by the action of the pawl *p* gas is free to pass to the igniter, communication having been established therewith through the holes *j* to the by-pass tube *k*, and in this position the main supply to the burner is shown half on during the supply to the igniter, but may be entirely turned off if desired by suitably arranging the ports in the valve. The next impulse will effect the turning-off and the valve will assume again the position indicated in Fig. 1.

Figs. 6 and 7 show a modification wherein is employed a plug provided with any suitable number of transverse holes to establish a communication between the source of supply and the by-pass or main, as the case may be, to the burner, a ratchet wheel being provided for intermittently rotating the plug as previously described in connection with the flat valve. In this case a plug valve *r* with a ratchet wheel *s* is arranged to be intermittently rotated to the extent of one tooth in two steps by any suitable means such as the pawls described in connection with Fig. 1.

Fig. 7 shows the valve *r* in the intermediate position establishing communication from the main *t* to *u* leading to the burner,

and also to the auxiliary burner or igniter through *v* the conditions being similar to those already described.

Fig. 8 shows another construction in which the valve *f* is a flat disk pierced with holes *w* arranged in a circle concentric with the center of the disk, and working pivotally on a base with similar holes *x*, and the whole inclosed in a gas-tight box *y*. One or more holes (such as *z* for example) in the base is or are arranged to establish communication with the secondary supply. In this modification electro-magnet coils are shown operating an armature *2* with suitable pawls *3, 4*. The valve is shown in the "off" position. Upon the operation of the armature *2* one of the holes *w* in the valve will first be brought opposite the holes *z* leading to the secondary supply. Upon the return of the armature *2* to the position of rest all the holes *w* will be brought opposite the holes *x* leading from the gas-tight box *y* to the main burner. But if desired the holes may be so arranged as to pass a supply of gas to the main burner during the intermediate position.

It will be understood that any suitable operating force may be used, not necessarily electric. For instance the movements may be actuated pneumatically by forcing a jet of air into a piston or elastic container arranged to take the place of the magnetic coils, or by utilizing the pressure of the gas acting on a diaphragm. Also that the igniter or by-pass may be arranged to be led out in any suitable manner, and that the proportions of the holes may be varied according to circumstances.

The apparatus with suitable modifications may be used for high or low pressure gas.

Claims:

1. In a gas controlling device, in combination, a main inlet conduit provided with a port, a main outlet conduit provided with a port, an auxiliary outlet conduit provided with a port, a rotatable valve provided with ports and passages communicating therewith, said valve being adapted to assume four positions, the ports of said valve and said conduits being so proportioned and arranged that in the first or normal position of the valve the ports of said main conduits are closed, in the second and fourth positions of the valve the main inlet conduit is in communication with the auxiliary outlet conduit and with the main outlet conduit and in the third position of the valve the main inlet conduit is in communication with the main outlet conduit and out of communication with the auxiliary outlet conduit, and valve actuating means for rotating said valve from its first position to its third position by one impulse of energy acting in two steps, and for rotating said valve from its

third position to its first position by a similar impulse of energy acting in two steps, the first step of the impulses moving the valve from its first position to its second 5 position or from its third position to its fourth position, and the second step of the impulses moving the valve from its second position to its third position or from its fourth position to its first position.

10 2. In a gas controlling device, in combination, a main inlet conduit provided with a port, a main outlet conduit provided with a port, an auxiliary outlet conduit provided with a port, a rotatable valve provided with 15 ports and passages communicating therewith, said valve being adapted to assume four positions, the ports of said valve and said conduits being so proportioned and arranged that in the first or normal position 20 of the valve the ports of said main conduits are closed, in the second and fourth positions of the valve the main inlet conduit is in communication with the auxiliary outlet conduit and with the main outlet conduit 25 and in the third position of the valve the main inlet conduit is in communication with the main outlet conduit and out of communication with the auxiliary outlet conduit, a ratchet wheel connected to said 30 valve, two oppositely acting pawls co-acting with said ratchet wheel, an electro-magnet, an armature therefor connected to said pawls, one of said pawls being operative and rotating said ratchet wheel when the armature is attracted, the other of said pawls being operative and rotating said ratchet wheel 35 when the armature is released and returns to its normal position, whereby said valve will be rotated from its first position to its third position by one impulse of energy acting in two steps and from its third position to its first position by a similar impulse of energy acting in two steps, the first step of the impulses moving the valve from its first position to its second 40 position or from its third position to its fourth position, and the second step of the impulses moving the valve from its second position to its third position or from its fourth position to its first position.

45 3. In a gas controlling device, in combination, a main inlet conduit provided with

a port, a main outlet conduit provided with a port, an auxiliary outlet conduit provided with a port, a rotatable valve provided with 50 ports and passages communicating therewith, said valve being adapted to assume four positions, the ports of said valve and said conduits being so proportioned and arranged that in the first or normal position of the valve the ports of said main conduits 55 are closed, in the second and fourth positions of the valve the main inlet conduit is in communication with the auxiliary outlet conduit and with the main outlet conduit, and in the third position of the valve the main inlet conduit is in communication with the main outlet conduit and out of communication with the auxiliary outlet 60 conduit, a ratchet wheel connected to said valve, two oppositely acting pawls co-acting with said ratchet wheel, an electro-magnet, 65 an armature therefor connected to said pawls, one of said pawls being operative and rotating said ratchet wheel when the armature is attracted, the other of said pawls being operative and rotating said ratchet wheel 70 when the armature is released and returns to its normal position, whereby said valve will be rotated from its first position to its third position by one impulse of energy acting in two steps and from its third position to its first position by a similar impulse of energy acting in two steps, the first step of the impulses moving the valve from its first position to its second position or from 75 its third position to its fourth position and the second step of the impulses moving the valve from its second position to its third position or from its fourth position to its first position.
